CLAIM

The ornamental design for a connector cable, as shown and described.

DESCRIPTION

FIG. 1 is a perspective view of our connector cable;

FIG. 2 is a top plan view thereof;

FIG. 3 is a bottom view thereof;

FIG. 4 is a right side view thereof;

FIG. 5 is a left side view thereof;

FIG. 6 shows internal detail of a USB connector. The shape and form of these internal pins is well known in the art and a cross sectional view is not required in this instance; and,

FIG. 7 is a back view thereof.

The broken line showing of four different plugs in the figures is for illustrative purposes only and forms no part of the claimed design.
